UNITED STATES PATENT OFFICE

WILLIAM M. SMITH, OF HERMOSA BEACH, CALIFORNIA

DESIGN FOR A GAME BOARD

Application filed October 16, 1931. Serial No. 41,405. Term of patent 14 years.

To all whom it may concern:

Be it known that I, WILLIAM M. SMITH, a citizen of the United States, residing at Hermosa Beach in the county of Los Angeles and State of California, have invented a new, original, and ornamental Design for a Game Board, of which the following is a specification, reference being had to the accompanying drawings, forming part thereof.

Fig. 1 is a top plan view of a game board showing my new design; and

Fig. 2 is a side elevation of the same.

I claim:

The ornamental design for a game board, as shown.

WILLIAM M. SMITH.
